SPACEBAND CLEANING MACHINE

Samuel Sofnas, Indianapolis, Ind.

Application April 2, 1945, Serial No. 586,246

11 Claims. (Cl. 51—157)

1

The present invention relates to a machine for clearing the space bands used in Linotype machines. As is well known in the art, there is a tendency for type metal to cling and accumulate at the casting point upon the sleeves of such space bands, and an accumulation of such metal has a deleterious effect upon the space bands and the matrices of the type font.

Various forms of means have been provided in the prior art for preventing or removing the accumulation of metal; but few if any of them have met with commercial success. It is still standard practice to remove the set of space bands from the space band box, periodically, and to clean and lubricate them by manually rubbing them upon a board coated with graphite. This operation is not only time consuming, but tedious; and the operator is very likely to become slovenly and neglect to clean the space bands as often as standard practice requires because of the monotony and arduousness of the operation.

The primary object of the present invention is to provide a machine so constructed as to support two or more space bands, and operable to clean the same by mechanically rubbing them against a plane surface coated with graphite, the rubbing operation being accomplished with a minimum of effort, and with automatic uniformity. Further objects of the invention are to provide specific details of improved structure in such a machine.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a longitudinal elevation of a machine constructed in accordance with the present invention, parts being broken away for clarity of illustration, and certain parts being shown in section;

Fig. 2 is a plan view of the machine of Fig. 1, parts being broken away; and

Fig. 3 is a fragmental transverse section taken substantially on the line 3—3 of Fig. 2.

In Fig. 2, I have shown a space band 10 of conventional construction, provided with the usual slide 11. In accordance with standard practice, the space band is formed at one end with a slot 12, and at its opposite end with the standard V-shaped notch 39; flanked by the shoulders 13 and 14.

2

The machine of the present invention comprises end walls 18 and 15, to which lateral enclosing walls are secured by bolts 17 and 19a or the like, one lateral wall 16 being shown fragmentarily in Fig. 1. End closure 18 supports removable bearings 18a for slide rods 20 and 21 at one end of a carriage 22; and end closure 15 at the opposite end of the frame work supports a removable bearing 18b for a slide rod 23 at the opposite end of said carriage. All of said bearings are secured to their respective end walls 18 and 15 by bolts 19. As is clearly to be seen, the carriage 22 is reciprocable within the frame or housing of the machine.

In the illustrated embodiment of the machine, two such carriages are mounted; but only one of them is fully shown. Corresponding parts of the second carriage are designated by primed numerals.

At one end of the carriage there are provided a pair of aligned, upstanding ears 24 and 25, supporting a rod 26 which is held against oscillation with respect to said ears by set screws 27 and 28. Interdigitated between said ears are a pair of ears 29 and 30, oscillatable upon said rod 26, and fixed with respect to a support 31. Thus, the support 31 is mounted upon the carriage 22 for oscillation about the axis of the rod 26.

The opposite end 32 of the support 31 is guided between a pair of plates 33 and 34 secured to a block 35 at the end of the carriage 22 opposite the position of the ears 24 and 25. Said end 32 of the support 31 is supported upon an adjustable screw 36, threadedly mounted in a boss projecting from the base of the carriage 22, and adapted to be held in adjusted position by a set screw 37.

Carried adjacent one end of the support 31 is a finger 38, engaging the pointed end of the notch 39 of a space band 10, said finger 38 being adjustably held in position upon the support 31 by an adjusting bolt 40. The bolt 40 passes through an elongated slot 40' in the side wall of the support 31, and engages the base 38' of the finger 38. Obviously, if the bolt 40 is loosened, that bolt, and therefore the finger 38, may be shifted longitudinally of the support 31, within the range of the slot 40'. Secured to the support 31 on opposite sides of a wooden pad 45 are a pair of posts 41 and 42 adapted to engage beneath the shoulders 13 and 14 of a space band when such space band is positioned on the pad 45 with its notch 39 snugly receiving the finger 38.

At the opposite end of the support 31 is mounted a finger 43 engageable in the notch 12 of the space band, said finger being adjustably po-

sitioned upon the support 31 through the medium of an adjusting bolt 44, the arrangement corresponding to that above described with the finger 38. Obviously, the parts 38 and 43 will be adjusted, in relation to the posts 41 and 42, to such positions that a space band of standard proportions and dimensions, when associated with said elements, will be stationarily held upon the wooden pad 45 secured to the uppermost face of the support 31 by means of screws 46, or the like. Incidentally, it is to be noted that the pad 45 is formed with opposed finger notches 47 and 48 to facilitate the placing of space bands upon said pad, and the removal of such space bands therefrom.

At one end of the frame there are provided upstanding aligned ears 49 and 50 adapted to support a rod 51, said ears being provided with set screws 52 and 53 for securing said rod against oscillation. A cover plate 54 is formed with aligned ears 55 and 56 adapted to straddle said ears 49 and 50 and to be journalled upon the rod 51. Collars 57 and 58 may be suitably secured to the projecting ends of the rod 51 to complete the hinging association of the cover 54 with the frame. At the end of said cover plate remote from said ears 55 and 56 there is provided a tongue 59 cooperable with a spring latch element 60; and there is further provided a handle 61 for manipulating said cover plate.

Substantially midway between the ends of the cover plate, said plate is formed with a port 62 vertically aligned with the carriage 22. Said port is guarded by a fitting 63 formed to provide a cylinder in which is reciprocably mounted a plunger 64.

Said barrel 63 further contains a spring 65 bearing against the upper end of said plunger 64, the opposite ends of said spring abutting against a cap 66 threadedly associated with the barrel 63. The cap 66 is perforated to permit the passage of a stem 67, which stem is a reduced portion of the plunger 64, said stem being headed, as at 68, by a disc threaded thereon. It will be seen that the spring 65 urges the plunger 64 always inwardly with respect to the cover plate 54, and that the disc 68 acts to limit the movement of the plunger 64 under the influence of the spring 65.

The inner end of the plunger 64 is slotted to receive an ear 69 pivotally mounted upon a pin 70 traversing the slotted end of said plunger. Said ear 69 is integral with a presser member 71 which is provided, adjacent its opposite ends, with upstanding plates 72 and 73 received, respectively, in openings 74 and 75 in the cover plate. Said openings are suitably guarded, in a manner later to be described, so that the plates 72 and 73 are permitted to move within their own plane, but are restrained against movement out of such plane. It will be noted, from an examination of Fig. 2, that the plane defined by said plates includes the axis of the plunger 64. Thus, the presser member 71 is guided for limited oscillation about the pivot pin 70, and for reciprocation in the axial line of the plunger 64, but is held against other movement with respect to the cover plate 54.

Secured to the under face of the presser member 71, by means of screws 77, or the like, is a wooden pad 76 formed to provide a plane surface parallel with the plane of movement of the carriage 22; and, when the cover plate 54 is closed, the spring 65 acts to urge said surface resiliently

into engagement with the exposed upper face of a space band 10 supported upon the pad 45.

A bracket 78 is secured, by means of bolts 79 or the like, to that end of the frame adjacent the hinge rod 51; and said bracket is formed to provide a bearing 80 in which is journalled the mid-portion of a shaft 81. Said shaft includes a reduced end portion 82 upon which is suitably fixed a gear 83; and a pin 84, threadedly secured to 10 said gear at a point eccentric with respect to the shaft extension 82, projects from the outermost face of said gear 83 and receives one end of a pitman 86. Said pin is headed at 85 to retain the pitman in place. The opposite end of said pitman 86 is journalled upon the rod 26, whereby 15 rotation of the shaft 81 will result in reciprocation of the carriage 22.

The opposite end of the shaft 81 is enlarged to form a wheel 88 which carries a headed pin 20 87 similar to the pin 85. A pitman 86' has one end mounted upon said pin 87 and has its opposite end associated with the companion carriage, in the same manner in which the pitman 86 is associated with the carriage 22. As shown, and 25 preferably, the pins 85 and 87 are equidistant from the shaft axis, but are peripherally spaced apart 180°, so that the two carriages will be equally and oppositely reciprocated, upon rotation of the shaft 81.

30 A second bracket 89, suitably secured to the frame by bolts 90 or the like, provides a hub 91 aligned with a hub 93 on the bracket 78, said hubs providing a journal mounting for a shaft 92. Said shaft carries a gear 94, whose pitch diameter is 35 preferably much greater than that of the gear 83, with which said gear 94 meshes. The gear 94 is held against axial movement upon the shaft 92 by a set screw 95 threaded into its hub, and said shaft, in turn, is held against axial movement by a collar 96 fixed to said shaft on one side of the hub 91, and a collar 97 fixed to said shaft on the other side of said hub 91. The collar 97 carries a crank 98, in the illustrated embodiment of the invention, whereby the gear 94 may 40 be rotated. Obviously, the shaft 81 may alternatively be driven from any source of power.

It will be clear that, in use, the spring latch 60 may be shifted to the left to release the tongue 59, whereupon the handle 61 may be manipulated 50 to raise the cover plate 54 about its hinge axis 51. This opens the machine, so that a pair of space bands 10 may be mounted upon the pads 45 of the two carriages. The plane surfaces of the pads 76 are then treated with graphite (and, if 55 desired, powdered graphite may also be sprinkled upon the exposed surfaces of the space bands); and the cover 54 is then closed, the spring latch 60 reengaging the tongue 59. Thus, the plane surfaces of the pads 76 are pressed against the 60 exposed surfaces of the space bands by the springs 65. Now, if the crank 98 is turned the two carriages will be equally and oppositely reciprocated, at relatively high speed, whereby the exposed 65 surfaces of the space bands are rubbed against the treated plane surfaces of the pads 76. Thus said space bands are quickly cleaned.

Now, the machine is reopened and the space bands are turned over to expose the surfaces which previously were in engagement with the 70 pads 45, the machine is closed, and the above operations repeated to clean such newly exposed surfaces.

I preferably construct the machine to permit various adjustments to compensate for slight 75 variations in the alignment of its associated parts.

Thus, as shown in Fig. 2, the barrel member 63' is formed with a base flange 99' provided with diametrically opposed slots 100' opening through the periphery thereof. Said flange 99' is secured in place on the cover plate 54 by means of bolts 101' engaged in said slots 100'. Obviously, if the bolts 101' are loosened, the barrel member 63' may be shifted, to some extent, transversely of the cover member; and after such adjustment is made, the bolts 101' may be retightened to secure the barrel member in place.

Similarly, the positions of the plates 72 and 73, transversely of the machine, are determined by the guard plates associated therewith. It will be remembered, in this discussion, that the primed numerals shown in Fig. 2 designate parts which correspond to similar parts associated with the carriage 22, but broken away in Fig. 2. Thus, a plate 102' is associated with one side of the opening 74', while a similar plate 103' is associated with the opposite side of said opening. Said plates 102' and 103' are formed with transversely extending slots 104' in which engage securing bolts 105' and 106'. With said bolts loosened, the plates 102' and 103' may be adjusted transversely of the cover plate 54, and when said bolts are tightened down, the plates will be held in adjusted position.

Associated with the opening 75' is a similar pair of plates 102'' and 103'' similarly adjustably securable in place upon the cover plate 54.

I claim as my invention:

1. A machine for cleaning space bands comprising a carriage, two laterally-spaced posts upstanding from said carriage and engageable with the shoulders of a standard space band, a finger upstanding from said carriage near said posts and intermediate the positions of said posts, a second finger on said carriage aligned with said first-named finger and longitudinally spaced therefrom, and independent means for securing said fingers in position on said carriage, said fingers being adjustable toward and away from each other and being respectively engageable in notches at opposite ends of such space bands, a presser element formed to provide a plane surface adapted to assume a position in cooperative relation to said carriage and in contact with the exposed face of such space band, means resiliently urging such surface into such contact, and means for reciprocating said carriage to rub said exposed space band face against said surface.

2. A machine for cleaning space bands comprising a frame, a pair of carriages mounted in said frame for substantially coplanar reciprocation, means on each of said carriages for supporting a space band, means providing a plane surface engageable with the exposed face of each of such space bands, and common means for reciprocating said carriages relatively in opposite directions to rub each of said space bands against its cooperating plane surface.

3. A machine for cleaning space bands comprising a frame, a pair of carriages mounted in said frame for substantially coplanar reciprocation, means on each of said carriages for supporting a space band, means providing a plane surface engageable with the exposed face of each of such space bands, rotatable means journaled on said frame, an eccentric carried by said rotatable means, a pitman connecting said eccentric with one of said carriages, a second eccentric carried by said rotatable means, said two eccentrics being equidistant from the axis of said rotatable means but being peripherally spaced apart

180°, and a second pitman connecting said second eccentric with said second carriage, whereby rotation of said rotatable means produces equal and opposite reciprocation of said two carriages.

4. A machine for cleaning space bands comprising a frame, a pair of carriages mounted in said frame for substantially coplanar reciprocation, means on each of said carriages for supporting a space band, means providing a plane surface engageable with the exposed face of each of said space bands, a shaft journaled substantially at its midpoint on said frame, a wheel fixed on one end of said shaft, an eccentric carried by said wheel, a pitman connecting said eccentric to one of said carriages, a second wheel fixed on the other end of said shaft, a second eccentric carried by said second wheel, and a pitman connecting said second eccentric to the other of said carriages, said eccentrics being substantially equidistant from the axis of said shaft but spaced apart peripherally substantially 180°, whereby rotation of said shaft produces equal and opposite reciprocation of said two carriages.

5. A machine for cleaning space bands comprising a frame, a pair of carriages mounted in said frame for substantially coplanar reciprocation, means on each of said carriages for supporting a space band, means providing a plane surface engageable with the exposed face of each of such space bands, a shaft journaled on said frame, a large gear fixed on said shaft, rotatable means journaled on said frame and including a smaller gear meshing with said first-named gear, an eccentric carried by said rotatable means, a pitman connecting said eccentric with one of said carriages, a second eccentric carried by said rotatable means, and a second pitman connecting said second eccentric with said second carriage, whereby rotation of said rotatable means produces reciprocation of both of said carriages.

6. A machine for cleaning space bands comprising a frame, a pair of carriages mounted in said frame for substantially coplanar reciprocation, means on each of said carriages for supporting a space band, means providing a plane surface engageable with the exposed face of each of such space bands, a shaft journaled on said frame, a large gear fixed on said shaft, a second shaft journaled substantially at its midpoint on said frame, a gear, smaller than said first-named gear, fixed on one end of said second shaft, an eccentric carried on the outer face of said gear, a pitman connecting said eccentric with one of said carriages, a wheel fixed to the other end of said second shaft, a second eccentric carried on the outer face of said wheel, and a second pitman connecting said second eccentric with the other of said carriages.

7. A machine for cleaning space bands comprising a frame, a carriage supported for reciprocation in said frame, and adapted to support a space band, a cover for said frame, means for releasably securing said cover in place on said frame, and a presser member formed to provide a plane surface engageable with a space band supported on said carriage, when said cover is closed, said cover being formed intermediate its ends with a perforation, a plunger reciprocably mounted in said perforation, means pivotally supporting said presser member on said plunger, spring means urging said plunger toward said carriage, and means limiting the degree of movement of said plunger under the influence of said spring means.

8. A machine for cleaning space bands com-

prising a frame, a carriage reciprocably mounted in said frame and adapted to support a space band, a cover for said frame, a presser member formed to provide a plane surface engageable with a space band supported on said carriage when said cover is closed, a plunger carried on said cover for reciprocation in a line normal to the plane of reciprocation of said carriage, spring means urging said plunger toward said plane, means limiting movement of said plunger in response to the tendency of said spring means, means pivotally supporting said presser member on said plunger on an axis parallel with said plane but transverse to the line of movement of said carriage, and means for guiding said presser member in its oscillation about said pivotal axis.

9. A machine for cleaning space bands comprising a frame, a carriage reciprocably mounted in said frame and adapted to support a space band, a cover for said frame, a presser member formed to provide a plane surface engageable with a space band supported on said carriage when said cover is closed, a plunger carried on said cover for reciprocation in a line normal to the plane of reciprocation of said carriage, spring means urging said plunger toward said plane, means limiting movement of said plunger in response to the tendency of said spring means, means pivotally supporting said presser member on said plunger on an axis parallel with said plane but transverse to the line of movement of said carriage, a pair of slots in said cover defining a line intersecting the axis of reciprocation of said plunger and parallel with the line of movement of said carriage, and a pair of studs associated with said presser member and guidingly received in said slots, respectively.

10. A machine for cleaning space bands comprising a frame, a carriage reciprocably mounted in said frame and adapted to support a space band, a cover for said frame, a presser member formed to provide a plane surface engageable with a space band supported on said carriage when said cover is closed, a plunger carried on said cover for reciprocation in a line normal to the plane of reciprocation of said carriage, spring means urging said plunger toward said plane, means limiting movement of said plunger in response to the tendency of said spring means, means pivotally supporting said presser member on said plunger on an axis parallel with said plane but transverse to the line of movement of said carriage, a pair of slots defining a line parallel with the line of movement of said carriage and defining a pair of studs associated with said presser member and guidingly received in said slots, respectively.

5 on said plunger on an axis parallel with said plane but transverse to the line of movement of said carriage, means adjustably carried by said cover adjacent its opposite ends and defining a pair of slots defining a line parallel with the line of movement of said carriage, and a pair of studs associated with said presser member and guidingly received in said slots, respectively.

10 11. A machine for cleaning space bands comprising a frame, a carriage reciprocably mounted in said frame and adapted to support a space band, a cover for said frame, a presser member formed to provide a plane surface engageable with a space band supported on said carriage when said cover is closed, means adjustably mounted on said cover and defining a cylinder whose axis, when said cover is closed, is substantially normal to the plane of reciprocation of said carriage, a plunger reciprocably mounted in said cylinder, spring means urging said plunger toward said plane, means limiting movement of said plunger in response to the tendency of said spring means, means pivotally supporting said presser member on said plunger on an axis parallel with said plane but transverse to the line of movement of said carriage, means adjustably carried by said cover adjacent its opposite ends and defining a pair of slots defining a line parallel with the line of movement of said carriage, and a pair of studs associated with said presser member and guidingly received in said slots, respectively.
